UNITED STATES PATENT OFFICE.

ARTHUR A. MCRAE, OF ATTLEBOROUGH, MASSACHUSETTS, ASSIGNOR TO
MCRAE & KEELER, OF SAME PLACE.

DESIGN FOR A STICK-PIN, &c.

SPECIFICATION forming part of Design No. 30,305, dated March 7, 1899.

Application filed February 9, 1899. Serial No. 705,119. Term of patent 31 years.

To all whom it may concern:

Be it known that I, ARTHUR A. MCRAE, of Attleborough, in the county of Bristol and State of Massachusetts, have invented and 5 produced a new and original Design for a Stick-Pin or Similar Article, of which the following is a specification, reference being had to the accompanying drawings, forming part thereof.

10 Figure 1 is a front view, and Fig. 2 is a vertical sectional view, showing my design.

The leading features of my design consist in the raised surface and outline representing a pumpkin with the nose, eyes, and mouth 15 of a face cut therefrom.

In the drawings, *a* indicates the main body of the stick-pin, having the outline and con-

figuration of a pumpkin; *b*, the nose; *c c*, the eyes; *d*, the mouth, and *e* the pin.

The whole design presents to the eye the 20 appearance of a Jack-o'lantern.

Having thus described my invention, what I claim as new, and desire to secure by Letters Patent, is—

25 The design for a stick-pin or similar article, substantially as herein shown and described.

In witness whereof I have hereunto set my hand.

ARTHUR A. MCRAE.
